UNITED STATES PATENT OFFICE.

ERASTUS EMERY, OF PITTSBURGH, PENNSYLVANIA.

BRAKE-SHOE KEY.

Application filed April 28, 1922. Serial No. 557,118.

To all whom it may concern:

Be it known that I, ERASTUS EMERY, residing at Pittsburgh, in the county of Allegheny and State of Pennsylvania, a citizen 5 of the United States, have invented or discovered certain new and useful Improvements in Brake-Shoe Keys, of which improvements the following is a specification.

It is the general practice to secure brake-10 shoes to brake-shoe heads by means of keys passing through lugs on the shoes and heads, it being the general practice to form two lugs on the head suitably spaced and one lug on the shoe adapted to pass between the lugs 15 on the head. The inner surfaces of these lugs against which the key will bear when in locked position, are made on arcs of circles, and by general consent the curvature of these surfaces as well as dimensions of the 20 shoes and heads have been standardized, as also the thickness and curvature of the tapering pin employed for locking the head to the shoe. As this pin, or key is usually formed by forging a rolling, it can be given 25 the exact standard dimensions and curvature. But as the heads and shoes are made by casting, it is practically impossible to insure that the standard dimensions will be complied with at all times, and hence a certain 30 allowance is made in the dimensions of the parts of the shoe and head. By reason of the construction above specified, the key will have only a line bearing on the inner surfaces of the lugs of the shoes and heads and 35 even if the dimensions and curvature of the lugs should conform to standard, the key is liable to work loose on account of its taper and also because it is substantially narrower than the widths of the openings 40 through the lugs on the brake shoe head and shoe. If the dimensions of the lugs do not conform to standard, then the liability of the keys working loose is increased.

The construction described and claimed 45 herein has for its object a construction of key whereby the latter may bear on the lugs of the head, while a portion which is intended to bear against the lug on the head is so constructed that a firm bearing of the key 50 on the lug will be insured regardless of permissible variations of dimensions of the lugs on the shoes and head. It is a further object of the invention to so construct the key as to prevent any lateral movement of the shoe 55 on the head. The invention is hereinafter more fully described and claimed.

In the accompanying drawings, forming a part of this specification, Fig. 1 is a sectional elevation of a brake-shoe and brake-shoe head secured together in proper relation by the improved key claimed herein; 60 Fig. 2 is a sectional view on a plane indicated by the line II—II, Fig. 1; and Fig. 3 is a detail view showing a modification of the key. 65

In the practice of the invention the brake-shoe head and brake shoe are formed according to standard dimensions. The head 1 is provided with lugs 3 and 4 having openings therethrough for the passage of the key and adjacent to its upper and lower ends with abutments 5 against which the shoe will bear when in position on the head. The brake shoe is provided with a lug 6 having an opening therethrough and adapted to project when the shoe is placed in position against the head between the lugs 3 and 4 on the head. In the standard construction the bearing surfaces *a* of the lugs 3 and 4 and the bearing surface *b* of the lug 6 are 70 formed on arcs of concentric circles and hence the surfaces *a* will, if the head conforms to standard dimensions, be parallel with the surface *b* on the shoe, if also of 75 standard dimensions, so that if a key, tapering from end to end, and having the same curvature longitudinally as that of the surfaces *a* and *b* of the head and shoe as in the present construction, were forced in through 80 these lugs to lock the shoe in position, the 85 key would have only line bearings on the respective lugs. If there were a departure, either from the curvature of these surfaces on the head and shoe respectively, or if these 90 surfaces did not conform to the standard as 95 regards their positions relative to each other and to the abutments 5, then the key when forced to its position would not bear in such manner on the surfaces of the lugs as to form 100 an effective and permanent lock. The improved key is made of substantially uniform thickness from end to end, such thickness being slightly less than the distances between planes coincident with the surfaces *a* and the surfaces *b*. In the construction shown in 105 Figs. 1 and 2 the key is formed by bending a strip of metal vertically in cross-section to substantially U-shape. The legs of the key adjacent to the head or loop 9 are bent inwardly so that the legs will be in contact for 110 a suitable distance and form a body portion 10. The legs and preferably the entire key

thus formed are curved longitudinally, such curvature corresponding or approximately corresponding to the curvature of surfaces *a* of the lugs 3 and 4 of the head and that of the surfaces *b* of the lugs on the shoe. Adjacent to their ends the legs are provided with inclined shoulders 11 preferably formed of outwardly bending legs and the portions 12 beyond the shoulders are so inclined inwardly that the distance between the ends of the portions 12 would be somewhat less than the widths of the slots or openings through the lugs on the head and shoe. These inwardly inclined portions are designed to facilitate the insertion of the key to locking position. When the key is driven in, the legs will be compressed until the shoulders pass beyond the lug 3 on the head, whereupon the legs will spring apart, the shoulders 11 passing behind the lug 3 on the head, thereby effectually locking the key as against movement in an unlocking direction. The legs extend from the body portion 10 with some divergence which is so proportioned that when the key has been inserted in the shoulders 11 and have passed beyond the lug 3 allowing the legs to spring apart, the outer surfaces of the legs will bear against the sides of the slots or openings through the lugs on the head and shoe and thus prevent any lateral movement of the shoe relative to the head.

The legs of the key have portions *c* and *d* spaced such a distance apart that they will bear on the surfaces *a* of the lugs 3 and 4 for a substantial extent when the key is in locking position. The portion *e* of the key intermediate these spaced portions *c* and *d* is off-set in such manner as to form inclined surfaces which will be tangential or approximately tangential to the longitudinal curvature of the legs and will operate as wedges bearing against the surface *b* of the lug on the shoe. This portion is off-set to such a degree that no matter how much the lugs may depart from standard dimensions, provided such departure is not greater than that allowed, these offset portions will bear against the lug 6 and portions on opposite sides of the off set will bear uniformly on the surface *a* of the lugs 3 and 4. The inclined portions *e* are so located with reference to the shoulders 11 that when the distance between a plane coincident with the surfaces *a* of the lugs 3 and 4 and a plane coincident with the surface *b* of the lug 6 correspond with a permissible departure below the standard, the inclined portions *e* will enter a short distance into the slots in the lug on the shoe when the shoulders 11 have passed behind the lug 3. If the dimensions of the head and shoe are standard or greater to a permissible extent, the inclined surfaces *e* will move farther into the slots or openings in the lug 6. As the head

and shoe are always in a substantially vertical position, the jarring to which they are subjected will cause the key to drop down until the inclined portions *e* bear against the lug 6.

70

In lieu of forming the key by bending a strip of metal as above stated, the key may be forged or stamped as shown in Fig. 3, the portion adjacent to the loop or handle 9^a being solid or integral and the lugs diverging from this solid or integral portion. In other respects, the key will be constructed substantially similar to the key shown in Figs. 1 and 2.

75

The improved key consists of a body portion which includes the loop or head 9 and the portion 10 or 10^a in the respective forms and resilient legs extending preferably in diverging lines from the body portion. The downward movement of the key will always be limited either by the inclined surfaces *e* or by the head or loop 9, and its outward movement in locking position would be prevented by the shoulders 11. When the key is in locking position, all portions thereof except the head or loop 9 are inaccessible and the key will be withdrawn only by an upward pull exerted on the head, which as stated, is provided with a loop or opening for the insertion of a bar or other tool when it is desired to withdraw the key.

80

It has heretofore been customary to form a lip on the upper end of the key, such loop being at right angles to the general plane of the key. This construction permits of the key moving down until the lip will strike against the lug on the shoe-head. In the construction shown herein the head 9 lies in the general plane of the key but projects laterally therefrom so that it will strike against the abutments 5 on the shoe-head and prevent any further movement downwardly of the key. It is characteristic of the improvement claimed herein that the portion of the key intermediate of the head 9 and the shoulders 11 on the lugs, is formed of a length approximately equal to the distance between the outer surface of the upper abutments 5 on the head and the lower lug 3, so that the key when in operative position, cannot move any material distance longitudinally either up or down. And further, the body portion is made of such a length between its head and the point of junction of the legs therewith that the legs will have a resilient bearing against the side walls of the openings through the lugs on the shoe-head and shoe, thus preventing any lateral movement of the shoe on the head.

100

Experience has shown that if the key were made U-shape, a blow on the closed end, unless directly in line with the key, would cause the leg most nearly in line with the blow to move down further than the other leg and the key will be distorted. This diffi-

130

culty has been overcome by bringing the legs into contact immediately below the closed end as shown in Figs. 1 and 2, or making the legs integral as shown in Fig. 3. It has

5 been found that even if the driving blow is not central or in line with the legs, the latter would move down uniformly and without distortion.

I claim herein as my invention:

10 1. A key for connecting a brake shoe to a brake shoe head having in combination a body portion and resilient legs extending from the body portion, said legs being curved longitudinally and having spaced 15 portions adapted to bear uniformly on lugs on the shoe-head and a portion intermediate the spaced portions so offset as to form inclined surfaces tangential or approximately tangential to the curvature of the legs for 20 engagement with the lug on the shoe.

2. A key for connecting brake shoes to brake shoe heads having in combination a body portion and resilient legs extending from the body portion, said legs being 25 curved longitudinally and having spaced portions adapted to bear uniformly on lugs on the shoe-head and a portion intermediate the spaced portions so offset as to form inclined surfaces tangential or approximately tangential to the curvature of the legs for 30 engagement with the lug on the shoe, the free ends of the legs being separated a distance greater than the widths of the openings in the lugs and provided with inclined shoulders adapted to engage one of the lugs on the 35 head and prevent longitudinal unlocking movement of the key.

3. A key for connecting a brake shoe to a brake shoe head having in combination resilient legs, a loop integrally connecting the legs at one end, said legs being substantially in contact adjacent to the loop forming the body portion, the portions of the legs extending from the body portion being curved longitudinally and adapted when in operative 45 position to bear against the side walls of the openings through the lugs on the head and shoe, and inclined shoulders on the legs adjacent to their lower ends, the legs having 50 spaced portions adapted to bear on the lugs on the head and portions intermediate the spaced portions so offset as to form inclined surfaces tangential or approximately tangential to the curvature of the legs for 55 engagement with the lug on the shoe.

4. A key connecting a brake-shoe to a brake-shoe head, said head and shoe having intercalating lugs intermediate their ends, said lugs having openings therethrough having in combination an upper body portion, resilient legs extending from the body portion and adapted to bear, when the key is 60 in operative position, against the side walls of the openings through the lugs on the shoe head and shoe, and a head at the upper

end of the key adapted to prevent the key from such longitudinal movement as will move the legs from a bearing with the upper lug on the head.

5. A key for connecting a brake shoe to a brake shoe head, said head and shoe having intercalating lugs intermediate their ends, said lugs having openings therethrough having in combination an upper body portion, resilient legs extending from the body portion and adapted when the key is in operative position to bear against the side walls of the openings through the lugs on the shoe-head, a head on the body portion and shoulders adjacent to the ends of the legs, said shoulders and head being adapted when the key is in operative position, to maintain the legs in contact with the side walls of the openings through the lugs on the head and shoe.

6. A key for connecting a brake shoe to a brake shoe head, said head and shoe having intercalating lugs intermediate their ends, said lugs having openings therethrough having in combination a body portion, a head extending laterally from the body portion, resilient legs extending from the body portion and adapted when the key is in operative position to bear against the side walls of the openings through the lugs on the shoe head and shoe, and shoulders adjacent to the lower ends of the legs, the portions of the legs beyond the shoulders being 90 inwardly inclined.

7. A key for connecting a brake shoe to a brake shoe head having in combination resilient legs, a loop integrally connecting the legs at one end, said legs being substantially in contact adjacent to the loop, thereby forming a body portion and the loop extending laterally from the upper end of the body portion to form a head, the portions of the legs beyond the body portion being adapted, when the key is in operative position, to bear against the side walls of the openings through the lugs on the brake shoe head and shoe.

8. A key for connecting a brake shoe to a brake shoe head having in combination resilient legs, a loop integrally connecting the legs at one end, said legs being substantially in contact adjacent to the loop, thereby forming a body portion and the loop extending laterally from the upper end of the body portion to form a head, the portions of the legs beyond the body portion being adapted, when the key is in operative position, to bear against the side walls of the openings through the lugs on the brake shoe head and shoe, and inclined shoulders on the legs adjacent to the lower free ends thereof.

In testimony whereof, I have hereunto set my hand.

ERASTUS EMERY.
